SANDAL

Clayton A. Laughlin, Minneapolis, Minn.

Application July 19, 1950, Serial No. 11,258

Term of patent 14 years

(Cl. D7—7)

To all whom it may concern:

Be it known that I, Clayton A. Laughlin, a citizen of the United States, residing at Minneapolis, Hennepin County, Minnesota, have invented a new, original, and ornamental Design for Sandal, of which the following is a specification, reference being had to the accompanying drawing, forming a part hereof.

Fig. 1 is a front perspective view of a sandal, showing my new design;

Fig. 2 is a top plan view thereof, the lacing shown in Fig. 1 being omitted from Figs. 2, 3 and 4 for convenience of illustration;

Fig. 3 is a front elevational view; and

Fig. 4 is a side elevational view of the opposite side shown in Fig. 1.

The shoes will be made in pairs, each pair consisting of a shoe for the left foot and a shoe for the right foot, the shoe for the right foot corresponding to the shoe for the left foot illustrated except for slight differences in contour.

I claim:

The ornamental design for a sandal, substantially as shown and described.

CLAYTON A. LAUGHLIN.
